UNITED STATES PATENT OFFICE.

IGNATIUS P. GALANTIN, OF CHICAGO, ILLINOIS, ASSIGNOR TO SPLITDORF ELECTRICAL COMPANY, OF NEWARK, NEW JERSEY.

IGNITION-GENERATOR.

1,303,469.

Specification of Letters Patent. Patented May 13, 1919.

Application filed November 16, 1918. Serial No. 262,759.

To all whom it may concern:

Be it known that I, IGNATIUS P. GALANTIN, a citizen of the United States, residing at Chicago, in the county of Cook and State 5 of Illinois, have invented certain new and useful Improvements in Ignition-Generators, for which the following is a specification.

This invention relates to an ignition generator of the permanent magnet type. In 10 starting internal combustion engines, particularly where they are not equipped with special cranking devices, the rotative speed is usually very low at the time when the engine is going over compression, which is the 15 time for firing the charge. This low rotative speed is detrimental to getting a good spark from a magneto ignition generator.

It is the object of my invention to provide 20 means for obtaining a good hot spark not only at the time of initial starting of the engine but at the extreme low speeds thereof.

While obtaining a good spark as above 25 pointed out, it is another object of my invention to properly time this spark so that the danger of back kick is entirely removed.

Another object of my invention is to provide means for attaching the starting or low 30 running speed means to the magneto generator in such a way as to facilitate easier installation of the magneto generator onto the engine.

A still further object of my invention is to provide means for entirely inclosing the 35 impulse device so that it will not be exposed to dust, dirt and other objectionable matter which tends to interfere with its operation.

Heretofore it has been customary to attach the starting means, which is generally 40 referred to as an impulse coupling, onto the driving end of the ignition generator, but according to my invention the driving end is left in the same condition as in the ordinary magneto without an impulse coupling, 45 by mounting the impulse device on the circuit breaker end of the magneto. In the application of my invention to a magneto, I have chosen to illustrate it in connection with a magneto of the Dixie type, such as 50 illustrated in U. S. Patent #1,126,676, of January 26, 1915, although it will be understood that the invention may be applied to other types of ignition generators.

In the drawings, Figure 1 is a perspective 55 view of the magneto looking at the cam end

but with the cover plate and impulse mechanism removed to show certain details.

Fig. 2 is a perspective view of the cover plate removed from the end of the magneto shown in Fig. 1. 60

Fig. 3 is a perspective view of the assembled impulse device as removed from Fig. 1.

Fig. 4 is a view of the driven member with the impulse and buffer springs in position. 65

Fig. 5 is a view of the driving member constituting a part of the impulse device shown in Fig. 3.

Fig. 6 is a view of the driving shaft showing a coupling member on the drive end. 70

Referring now to the details, wherein like numbers refer to corresponding parts in the various views, 1 is a magneto having a distributor block 2 illustrated as of the four cylinder type by the terminals 3 attached thereto. The block 2 is fastened to the end plate of the magneto as by screws 4. The rotating part of the magneto is hollowed and adapted to receive the driving shaft 5 on the drive end of which the coupling member 6 75 is adapted to be fastened in any suitable manner.

The opposite end of the shaft 5 is provided with a pin 7 adapted to fit in the slot 8 of the driving member 9. Threads 10 are cut on the shaft 5 adjacent to the pin 7 80 to receive a nut for holding the driving member 9 in position on the end of the shaft 5. The driven member 11 has, projecting from the back side thereof, a hollow stud 12 which carries a cam 13 securely fastened 85 to the stud 12 and to the driven member 11. The outer end of the stud 12 is slotted at 14 so as to leave arcuate segments 15 that are adapted to fit within arcuate slots 16 cut in the end of the rotating member of the magneto when the driven member 11 is inserted 90 in place on the end portion 17 of the shaft 5. The driven member 11 carries an impulse spring 18 and a buffer spring 19. The impulse spring 18 is adapted to be compressed by the pin 20 rigidly fastened to the driving member 9 and in fact the construction of the driving and driven members with the springs is similar to that shown and described in Patent #1,226,933, issued May 22, 105 1917, to Fred B. Williams, with the addition of the stud and cam on the back of the driven member 11 as above described.

Attached to the frame work of the magneto 1 is a movable breaker arm 21 carry- 110

ing a contact 24 and a stationary member 23 carrying contact 22. The arm 21 carries a bumper 25 that is engaged by the cam 13 on the rotation of the driven member 11.

- 5 The end plate of the magneto 1 has a projecting housing 26 adapted to receive the lower part 27 of a cover plate, the same being fastened to the housing 26 by screws passing through the screw holes 28. The 10 upper part 29 of the cover plate is formed to fit in the groove 30 in the distributor block 2. Mounted within the upper portion 29 is a tripping device 31 consisting of a pivoted dog 32 which is adapted to engage the 15 notches 33 in the driven member 11.

From the above description it will be seen that the drive shaft 5 is connected to the rotatable part of the magneto through the medium of the pin 7 engaging the slot 8 on 20 the driving member 9 and the impulse spring 18 abutting against the pin 34, since the driven member 11 is fastened to the rotatable part of the magneto through the means heretofore described.

- 25 Coming now to the operation of my invention when it is desired to use the impulse device, the tripping device 31 is set in the position shown in Fig. 2, by means of the push button 35 and the dog 32 will engage 30 one of the notches 33 as the driving and driven members are rotated by the shaft 5. The engagement of the dog 32 with the notches 33 will prevent the driven member, and thereby the rotatable member of the 35 magneto, from rotating while the driving member 9 which is fastened to the shaft 5 is driven forward in advance of the driven member until either one of the cams 36 comes under the dog 32 lifting it out of 40 either of the notches 33. As soon as the driven member 11 is released under the impulse of the spring 18 it will be rapidly advanced until it catches up with the driving member 9.

- 45 Substantially coincident with the time of catching up of the member 11 with the member 9 the cam 13 engaged the bumper 25 opening the circuit breaker and causing the magneto to produce its spark in the usual 50 and well known manner. After this has happened and the engine has obtained a certain predetermined speed, the number and strength of blows received on the dog 32 will throw it upward so that the pivotal line 55 A—B will pass beyond the line C—D and under the influence of the spring 37 the dog will be held out of engaging position with the driven member 11. In some cases, I prefer to mount on the back of the member 60 11 a centrifugally operated member 38 which may take the place of the button 35; that is to say, in starting, the nose 39 of the member 38 projects outwardly from the periphery of the driven member 11 so as to engage

the notch 40 on the tripping device 31, thereby tripping it down into the position shown in Fig. 2. After the engine has started the member 38 being pivoted at 41 will tend to rotate about this point so that the nose 39 will drop below the outer periphery of the 70 driven member 11 thereby being out of the path of engagement of the notch 40 on the tripping device 31. As soon, however, as the speed of the engine lowers to a predetermined point, the member 38 will drop 75 downward to the position shown in Fig. 3 and the nose 39 will engage the notch 40 and bring the tripping device back into operation to deliver hotter sparks.

The lower part of the cover plate 27 is 80 preferably provided with an opening 42 in which a glass may be set for the purpose of observing the operation of the parts inclosed within the housing 26 and cover portion.

Since the cam which operated the circuit breaker is carried on the driven member the circuit breaker will not be operated and consequently the spark will not be produced until after the driven member has been tripped and advanced to a point where the 90 engine has gone over compression so that no back kick will be obtained. It will easily be seen that the driving and driven members being housed in completely, as described, are not likely to become disabled by dirt, water 95 and other disabling agents.

While I have shown a preferred form of the application of my invention it will be understood that numerous changes may be made in the application and in the details 100 entering therein, without departing from the spirit of the invention and scope of the appended claims.

Having thus described my invention, what I claim is:—

1. In an ignition generator having a hollow rotatable operating member, a driving shaft extending through said hollow member, a driving member fastened to said shaft, a driven member supported on said shaft and having a driving engagement with the generator rotatable member, resilient means associated with the driving and driven members, means for causing a relative displacement between the driving and driven members and storing energy in the resilient means and means for releasing the displacing means so the stored energy in the resilient means will act on the driven member to rapidly restore it to normal position for the 115 purpose described.

2. In an ignition generator having a hollow rotatable operating member, a driving shaft extending through said hollow member, a driving member fastened to said shaft, a driven member supported on said shaft and having a readily detachable driving engagement with the generator rotatable 120 125

- member, resilient means associated with the driving and driven members, a trip arranged to successively arrest said driven member to thereby place the resilient means under tension and means for automatically shifting said trip to release said driven member for the purpose described.
3. An ignition generator as specified in claim 1 in combination with stationary and movable circuit breaker members carried on the generator adjacent the driven member which carries a cam for operating the movable circuit breaker member as described.
4. An ignition generator as specified in claim 2 in combination with stationary and movable circuit breaker members carried on the generator adjacent the driven member which carries a cam for operating the movable circuit breaker member as described.
5. An ignition generator as claimed in claim 3 in which the circuit breaker, driving and driven members with correlated parts are inclosed within a protecting housing.
6. An ignition generator as claimed in claim 4 in which the circuit breaker, driving and driven members with correlated parts are inclosed within a housing including a cover carrying the trip mechanism.
7. An ignition generator as claimed in claim 1 in which the driving and driven members with correlated parts are inclosed within a housing including a part integral with the generator frame and a removable cover.
8. An ignition generator as claimed in claim 2 in which the driving and driven members with correlated parts, are inclosed within a housing including a part integral with the generator frame and a removable cover carrying the trip mechanism.
9. An ignition generator as claimed in claim 2 further characterized in this, that the driven member carries a device responsive to the speed of the generator for bringing said trip into action at a predetermined minimum speed of the generator.
10. An ignition generator as claimed in claim 8 in which the removable cover has an inspection device set therein.
11. An ignition generator having a rotatable member and an impulse starting coupling, consisting of driving and driven members with an associated impulse spring, mounted on an operating shaft on the opposite side of the generator from its drive end, said operating shaft being fastened to the driving member and the rotatable generator member to the driven member and means for causing the spring to give impulses to the generator rotatable member for the purpose described.
12. An ignition generator having a rotatable member, a circuit breaker and an impulse starting coupling, consisting of driving and driven members with an associated impulse spring, mounted on an operating shaft adjacent the circuit breaker, said driving member being connected to the operating shaft and the driven member to the generator rotatable member, means for causing the spring to give impulses to the driven member and generator rotatable member and a cam on the driven member for operating the circuit breaker.

In witness whereof, I affix my signature.

IGNATIUS P. GALANTIN.
